[57] CLAIM

The ornamental design for a chaise, as shown and described.

DESCRIPTION

FIG. 1 is a side elevational view of the chaise comprising my new design, the opposite side elevational view being a mirror image;

FIG. 2 is a top plan view thereof;

FIG. 3 is a front elevational view thereof;

FIG. 4 is a back elevational view thereof; and,

FIG. 5 is a bottom view thereof.

The broken lines depicting leg members are for illustrative purposes only and form no part of the claimed design.
